SYNTHESIS OF N-SUBSTITUTED 2-AMINO-ETHANETHIOSULFURIC ACIDS

Daniel L. Klayman, Chevy Chase, Md., and W. Franklin Gilmore, Oxford, Miss., assignors to the United States of America as represented by the Secretary of the Army No Drawing, Application June 17, 1968, Ser. No. 737,358, now Patent No. 3,595,899, dated July 27, 1971, which is a continuation-in-part of application Ser. No. 506,291, Nov. 3, 1965. Divided and this application July 15, 1969, Ser. No. 870,883

Int. Cl. C07c 141/00

U.S. CL. 260—453 R

1 Claim

ABSTRACT OF THE DISCLOSURE

A process for the synthesis of N-substituted 2-aminoethanethiosulfuric acids of the formula:

wherein R represents alkyl or phenyl alkyl by reacting ammonium thiosulfate with a 1-substituted aziridine. The compounds made by this process are effective antiradiation agents for animals.

The invention described herein may be manufactured and used by or for the Government for governmental purposes without the payment to us of any royalty thereon.

CROSS REFERENCE TO RELATED APPLICATIONS

This is a divisional application of application Ser. No. 737,358, filed June 17, 1968 (now U.S. Pat. 3,595,899, issued July 27, 1971), which is a continuation-in-part application of application Ser. No. 506,291, filed Nov. 3, 1965, now abandoned.

BACKGROUND OF THE INVENTION

(1) Field of the invention

It has been discovered that N-substituted aminoethanethiosulfuric acids of the general formula:

wherein R represents an alkyl, preferably having from 1 to 18 carbon atoms, or a phenyl alkyl wherein the alkyl chain has from 1 to 6 carbon atoms, are effective anti-radiation drugs for mammals.

(2) Description of the prior art

Destruction of cellular components from radiation exposure has been thought to result either because the radioactive particles cause the direct inactivation of some essential component of the cell by ionization, or indirect inactivation by an intermediate which is produced by radiation and which then reacts with a critical component. See Thomson, Radiation Protection in Mammals, 5, Reinhold Publishing Co. (1962).

It has been found that certain chemicals, introduced into the body prior to exposure, act as protective agents thereby permitting the body to sustain an amount of radiation which would constitute a lethal dosage without the introduction of said chemical compounds.

Laboratory experiments use as a criterion a 30 day

2

LD_{100} . This term is defined as that amount of radiation required to cause the death of all of the exposed subjects within 30 days. For example, to cause the death of 50 percent in 30 days the LD_{50} for mice varies from 400 to 700 roentgens (hereinafter referred to as r.) depending on the strain. The LD_{50} for some strains of guinea pigs is about 200 r. and around 800 r. for rabbits. The 30 day LD_{50} for man is estimated at between 400 and 500 r. Exact data depends on many variables such as age, sex, and diet.

See Thomson, p. 10. Other meaningful criteria involve a correlation between the dose rate in milligrams per kilogram of body weight and percent survival.

Laboratory procedure in evaluating a chemical as a radiation protective agent usually follows the procedure of injecting a sublethal dose of the chemical dissolved in water into groups of subjects, and then evaluating the new LD for the exposed animals. The activity of a chemical protective agent is evaluated on the basis of the increased LD after injection with the agent, against a control group. For example, Smith et al. in 73 Proc. Sec. Exptl. Biol. Med. 198 (1950) disclosed that 1000 r. given an animal previously treated with 1200 mg./kg. of cysteine will produce the same degree of mortality as 600 r. in an untreated animal (cited in Thomson, p. 56).

It is known that various thiols are effective antiradiation compounds. See Thomson, p. 53. Rosenthal in U.S. Pat. No. 3,284,297, issued Nov. 8, 1966, disclosed that 2-N-methylammoniummethylthiosulfuric acid was an effective antiradiation compound. However, research in the area of thiosulfuric acids was abandoned due to the fact that an enormous dosage of around 300 mg./kg. was necessary with the lower alkyl substituent in order to achieve only a 70 percent survival ratio.

SUMMARY OF THE INVENTION

It has now been discovered that certain higher alkyl and phenyl alkyl N-substituted 2-aminoethanethiosulfuric acids are particularly effective antiradiation drugs having a high LD, and a high efficiency for a relatively small dosage. These new compounds are also synthesized according to three new processes hereinafter described.

Accordingly, it is an object of this invention to synthesize the N-substituted family of 2-aminoethanethiosulfuric acids.

It is another object to provide N - substituted 2-aminoethanethiosulfuric acids for use as antiradiation drugs.

It is a further object to provide N-substituted 2-aminoethanethiosulfuric acids having low toxicity for mammals, and highly efficient antiradiation properties in mammals.

These and other objects will be obvious with reference to the following description.

DESCRIPTION OF THE PREFERRED EMBODIMENTS

The following table lists fifty-one compounds synthesized according to the processes of the invention and compiles the results of tests according to standard laboratory procedures on test groups of rodents. The table compares radiation dosage with drug dosage per kilogram of body weight to achieve percent survival or efficiency. The table also contains toxicity data in terms of an LD_{50} evaluated over 1 or 2 days. The period of time is short because the rodents normally die within one day. The data was complied using ordinary laboratory procedures.

Compound	Formula	Rodent drug dose (mg./kg.)	Radiation dose(r)	Time interval (min.)	Percent Survival	LD ₅₀ (mg./kg.)
1. Methyl	C ₃ H ₉ NO ₃ S ₂	300	800	15	70	350

The following example illustrates this invention.

EXAMPLE I

Preparation of methylaminoethanethiosulfuric acid

1-methylaziridine (5.71 g., 0.10 mole) was added to a stirred mixture of 18.53 g. (0.125 mole) of ammonium thiosulfate and 250 ml. of methanol. The entire mixture was heated for 4 hours during which time ammonia was evolved. The excess ammonium thiosulfate was removed by filtration and the filtrate was evaporated to dryness. The residue was recrystallized from water-ethanol to give 8.8 g. (51.4 percent) of methylaminoethanethiosulfuric acid, melting point 165° C. The infrared spectrum was identical to that obtained from the product made by another method.

Analysis.—Calcd. for C₃H₉NO₃S₂ (percent): S, 37.45. Found (percent): S, 37.51.

This procedure may be applied to the preparation of the N-substituted acid from 1-substituted aziridine having a substituted alkyl group with from 1 to 13 carbon atoms or a phenyl alkyl group wherein the alkyl chain has from 1 to 6 carbon atoms.

We claim:

1. A process for the synthesis of N-substituted aminoethanethiosulfuric acid of the formula:

wherein R is a member selected from the group consisting of linear alkyl having 1 to 4, 7 to 10, and 13 carbon atoms, branched alkyl having from 8 to 11 carbon atoms, and phenyl alkyl wherein the alkyl chain has from 1 to 6 carbon atoms comprising:

(a) reacting at reflux temperature in methanol solution

a molar excess of ammonium thiosulfate with a 1-substituted aziridine of the general formula:

wherein R is a member selected from the group consisting of linear alkyl having 1 to 4, 7 to 10, and 13 carbon atoms, branched alkyl having from 8 to 11 carbon atoms, and phenyl alkyl wherein the alkyl chain has from 1 to 6 carbon atoms, until N-substituted aminoethanethiosulfuric acid is formed; and

(b) isolating said N-substituted aminoethanethiosulfuric acid from the mixture recited in step (a) by removing the unreacted ammonium thiosulfate by filtration followed by evaporation of the filtrate to dryness.
